UNITED STATES PATENT OFFICE.

WILLIAM J. REGAN, OF PITTSBURGH, PENNSYLVANIA, ASSIGNOR TO THE MC CONWAY & TORLEY COMPANY, OF PITTSBURGH, PENNSYLVANIA, A CORPORATION OF PENNSYLVANIA.

DRAFT GEAR.

Application filed May 9, 1923. Serial No. 637,807.

My invention relates to draft gear for railway cars and has for its object to provide a simple, strong and easily manufactured mechanism especially well suited for application to passenger cars and for the employment of cushioning devices of the friction type.

A primary feature of the invention, generally stated, consists in the combination of a yoke device provided with arms adapted to receive between them the rear end of the car coupler, a car coupler formed with a recessed or bifurcated rear end extending between said arms, a follower having a forwardly extending slotted tongue disposed in interleaved relation to the bifurcated end of the coupler, and a pin passing through the yoke device, coupler and follower, the pin being so related to the follower tongue that it is in double shear at the beginning of a draft movement of the coupler and in quadruple shear at the end of such draft movement.

A further feature of the invention consists in constructing a draft gear with a yoke device having a friction casing and a plurality of slotted arms integrally united to said casing and extending forwardly therefrom, and in combining therewith a car coupler whose rear end is received between the arms, a follower movably mounted between said arms in advance of the casing and having a forwardly extending projection provided with a curved bearing face, and means for pivotally connecting the coupler and said yoke device, the rear end of said coupler being curved and adapted to engage the curved bearing face upon the follower.

Other features of invention, residing in particular combinations of parts and details of construction will hereinafter appear and be pointed out in the claims.

In the drawings illustrating the preferred form of the invention,

Figure 1 is a plan view of draft gear embodying the invention showing its relation to the stationary parts of the car with which it is associated.

Figure 2 is a view partly in side elevation and partly in vertical section of the construction shown in Fig. 1.

Figure 3 is a horizontal central section of a portion of the device.

Figure 4 is a vertical central section of the portion of the device illustrated in Fig. 2, the draft casting which is carried by the car sills being omitted.

Figure 5 is a vertical transverse section taken through the pivot pin connecting the coupler and yoke device, the draft casting being shown in end elevation.

In the drawings, 1 indicates the stem of a car coupler and 2 is the preferred form of yoke device with which it is associated. This yoke device, which is most advantageously formed as an integral casting, is preferably constructed with a hollow casing portion 3 made of any desired size or form suitable for receiving and cooperating with springs and friction elements housed thereby, the draft gear members that are located within the casing and which are operatively interposed between the rear end of the latter and the longitudinally movable follower 4, being diagrammatically indicated by the diagonally extending dotted lines 5 in a conventional manner.

Integrally united to said casing and extending forwardly therefrom are a pair of yoke arms 6 adapted to overlap the rear end of the coupler 1 on opposite sides thereof. The arms are respectively provided with apertures 7 for receiving the pin 8 by which the car coupler is connected to the yoke device, the said apertures preferably being in the form of slots permitting the said pin to travel rearwardly therein when the coupler is subjected to buffing in service and the said pin preferably constituting a pivot. The arms 6 may advantageously be integrally united at their forward ends on opposite sides by forwardly diverging tie members or walls 9, thus providing in conjunction with the said arms 6 a forwardly flaring recess adapted to receive the rear end of the car coupler and permit lateral swinging thereof.

The inner end of the coupler 1 is bifurcated to form a rearwardly opening recess 10 for receiving a tongue 11 with which the follower 4 is provided. The jaws of the coupler stem above and below the recess 10 are provided with suitable vertically aligned apertures 12 for receiving the pivot pin 8, and the rear ends of said jaws are formed with curved bearing faces 13 adapt-

ed to transmit buffing shocks to the follower 4 in any position which the coupler may assume on straight or curved track.

The follower 4, which is adapted to be actuated by the car coupler upon a buffing movement of the latter, and which during such movement preferably slides rearwardly with respect to the yoke device, is provided with a centrally disposed forwardly extending projection 14 forming a buffing bearing for the rear end of the coupler stem 1, the said projection being fashioned at its outer end upon opposite sides of the follower tongue 11 with curved bearing surfaces or seats 15 which are respectively adapted to cooperate with the correspondingly curved bearing faces 13 of the coupler. The tongue 11 which is integrally united to the follower 4 projects forwardly beyond the buffing bearings 15 and enters the recess 10 at the rear end of the coupler stem, thus being associated with the said stem in interleaved relation. The tongue 11 is provided with a longitudinally extending slot 16 through which the pivot pin 8 passes, the said slot being of such length that the pivot pin 8 reaches the end thereof and communicates draft strains to the follower 4 when the coupler 1 is pulled forward in draft to or substantially to the limit of draft gear movement. During a buffing movement the coupler and follower move rearwardly together and the pivot pin 8 does not slide in the slot 16 of the follower tongue, but during said movement the pivot pin slides rearwardly in the slots 7 of the yoke arms 6, thus permitting the coupler and its abutting follower to move rearwardly with respect to the yoke device.

The laterally projecting ends of the follower 4 respectively cooperate with suitable follower stops 17 which are rigidly secured to the center sills or draft sills 18 of the car. These follower stops form abutments for preventing forward movement of the follower when the coupler is pulled out in draft. Rearward movement of the yoke device 2 in buffing is preferably prevented by a back stop member or abutment 19 extending between and secured to the sills 18 and adapted to engage the rear end of the casting portion 3 of the said yoke device. The follower stops 17 and the back stop 19 are preferably integrally united to form a unitary draft casting by means of bars or plates 20 which may closely border the casting 3 of the yoke device so as to maintain the position and operative alinement of the latter.

The pivot pin or tail pin 8 is preferably inserted from below and may advantageously be supported by a bolt 21 running lengthwise of the yoke device and passing through perforated lugs 22 which are

preferably cast integral with the lower yoke arm 6 of the yoke device. A cotter 23 serves to retain the bolt 21 in assembled position.

In buffing the coupler 1 forces the follower 4 rearwardly while the yoke device, which bears at its rear end against the back stop 19, remains stationary. The cushioning elements which are operatively interposed between the follower and the yoke device 2 are thus actuated. When the coupler is pulled forwardly in draft the follower 4 remains seated upon the follower stops 17 and the yoke device is drawn forward with the coupler, thus again actuating the cushioning elements interposed between the follower and the yoke device. At the beginning of the draft movement of the coupler 1 the pivot pin 8 travels forwardly in the slot 16 of the follower tongue 11 and the pin acts in double shear, the shearing sections thereof being in the planes passing between the stem of the coupler and the yoke arms 6. But when the coupler has been pulled forward to the limit of draft gear movement or nearly so, the central portion of the pivot pin 8 pulls against the follower tongue 11 and thus calls into play two additional shearing areas of the pin, thereby placing the pin in quadruple shear and transmitting an uncushioned portion of the draft strain to the draft lugs or follower stops 17 directly through the follower 4. By this means the strength of the pivotal connection of the coupler to the yoke device is greatly enhanced to resist maximum strains.

My invention renders it practicable to provide a draft gear with a combined draft yoke and friction casing formed as an integral casting. Within the limits of space allowed in car construction the friction casing may be made of comparatively great length, and sufficiently large openings may be provided in the draft yoke device to permit springs and friction elements to be readily introduced into the casing. A reduction in the number of parts and in the weight and cost is also effected.

I claim:

1. A draft gear involving a yoke device, a follower movable with respect to said yoke device and adapted to be actuated by and to be movable with respect to a car coupler associated therewith, and means extending through said follower for connecting the coupler to said yoke device, a portion of said coupler being adapted to be interposed between said follower and said yoke device.

2. A draft gear involving a yoke device, a follower movable with respect to said yoke device and adapted to be actuated by a car coupler associated therewith, said coupler having a bifurcated rear end, and means extending through said follower for movably connecting said yoke device to the coupler,

said follower having a slotted tongue adapted to project into the bifurcated end of said coupler and through which said means extends.

5 3. A draft gear involving a yoke device, a follower adapted to be actuated by a car coupler upon a buffing movement thereof, and means interposed between and slidably connecting said follower and coupler for causing uncushioned draft strains to be transmitted to said follower from said coupler after a predetermined movement of said coupler.

4. A draft gear involving a yoke device, 15 a follower movable with respect to said yoke, a car coupler, and a pin connecting said yoke device, follower and coupler, said follower being provided with an elongated slot for receiving said pin to permit the latter 20 to move a predetermined distance with respect to said follower in the direction of draft movement of the coupler.

5. A draft gear involving a yoke device having a plurality of slotted arms, a car 25 coupler extending between said arms, a follower movably mounted between said arms and adapted to be actuated by said coupler, and a pin for operatively connecting said yoke device, coupler and follower, said follower being provided with a slotted portion 30 for receiving said pin, said slotted portion being adapted to be overlapped on opposite sides by portions of said coupler, and said pin extending through said coupler and entering the slots of said arms and being non- 35 simultaneously movable in the slots of said arms and in said follower slot.

6. A draft gear involving a yoke device having a plurality of slotted arms, a coupler 40 having a stem provided with a rearwardly opening recess, a follower having a slotted tongue extending into said recess, and a pivot pin passing through said coupler and through the slot of said tongue and having 45 its opposite ends projecting into the slots of said arms.

7. A draft gear involving a yoke device having a plurality of arms adapted to receive a car coupler between them, a car coupler having a stem provided with a rearwardly opening recess, a follower having a slotted tongue extending into said recess, and a pivot pin passing through said slot for pivotally connecting said coupler to said 50 follower and said arms, said pin being movable in said slot a predetermined distance when the coupler is subjected to draft.

8. A draft gear involving a yoke device, a 55 follower, a car coupler adapted to move said follower in buffing, and a pin for pivotally connecting said coupler, yoke device and follower, said follower being provided with a slotted tongue through which said pin extends and having on opposite sides of said 60 tongue curved shoulders adapted to form

buffing bearings for the rear end of said coupler.

9. A draft gear involving a yoke device having a forwardly flaring recess adapted to receive the rear end of a car coupler, a 70 follower, a car coupler extending into said recess and adapted to actuate said follower in buffing, and a pin for pivotally connecting said yoke device and coupler, said coupler and follower being provided with interleaved portions through which said pin extends.

10. A draft gear involving a yoke device, a car coupler, a follower movable with respect to said yoke device and adapted to be 80 actuated by said coupler in buffing, and a pin operatively associated with said coupler, yoke device and follower, said pin being adapted to afford greater shearing area to resist draft strains at the end of a draft 85 movement of the coupler than at the beginning of such draft movement.

11. A draft gear involving a yoke device provided with arms adapted to receive the 90 rear end of a car coupler between them, a car coupler having a bifurcated rear end extending between said arms, a follower having a slotted tongue disposed in interleaved relation to the bifurcated end of said coupler, and a pin extending through said yoke device, coupler and follower, said pin at the beginning of a draft movement of 95 said coupler being in double shear and at the end of the draft movement of said coupler being in quadruple shear.

12. A draft gear involving a yoke device having a friction casing and a plurality of arms integrally connected to said casing and extending forwardly therefrom and adapted to receive the rear end of a car coupler between them, a follower movably mounted between said arms in advance of said casing, tie members spaced from the forward end of said casing and integrally uniting said arms, and means for connecting said yoke device 100 and coupler, said follower being provided with a forwardly extending projection forming a buffing bearing for said coupler and having in advance of said buffing bearing a 105 tongue adapted to be connected to a car coupler.

13. A draft gear involving a yoke device having a friction casing and a plurality of arms integrally united to said casing and extending forwardly therefrom and adapted to receive the rear end of a car coupler between them, a follower movably mounted between said arms in advance of said casing and having a forwardly extending projection provided with a forwardly facing curved surface and also having a tongue extending forwardly from said curved surface, a car coupler adapted to be connected to said tongue and having a curved bearing face at 115 its rear end adapted to cooperate with the 120

125
130

curved surface of said follower, and means for pivotally connecting said coupler and said yoke device.

14. A draft gear involving a yoke device, a car coupler, a follower movable with respect to said yoke and adapted to be actuated by said coupler in buffing, and a pin adapted to communicate draft force from said coupler to said yoke and follower, said pin being adapted to operate in double shear and

also in quadruple shear.

15. A draft gear involving a yoke device, a car coupler, a follower movable with respect to said yoke and adapted to be actuated by said coupler in buffing, and means movably connecting said coupler and follower and adapted to directly transmit draft force to the latter.

In testimony whereof I affix my signature.

WILLIAM J. REGAN.
